RAILWAY CAR TRUCK BOLSTER
STABILIZER

Karl M. Hamilton, Chicago, Ill.

Application June 26, 1946, Serial No. 679,327

13 Claims. (Cl. 105—197)

1

My invention relates to car truck bolster stabilizing means for controlling excessive oscillation of the bolster relative to the truck frame and involving spring means for maintaining a frictional relation between the stabilizing means, carried by the bolster, and the truck frame independently of the bolster spring suspension or bolster supporting springs.

The invention more specifically stated involves providing the bolster adjacent its ends with suitable pockets having openings through the sides and bottom of the bolster and the pockets provided with transversely slidable friction shoes or blocks adapted to effect frictional contact with the bolster top wall and the adjacent portions of the truck frame through the action of a single wedge element or block which in turn is yieldingly forced and maintained in wedging position through the action of suitable spring means which, together with the friction blocks and wedge block, are all mounted within the bolster and independent of any external elements.

My invention has for its object the provision of bolster stabilizing means of simple construction and arrangement adapted for application to constructions at present in use and to a standard A. A. R. bolster and truck frame without necessitating change in height and width of the standard equipment and which permits the use of the standard bolster spring grouping and hence enables the use of a comparatively small spring plate and narrower width of side frame spring seat, or standard length of spring plank, if the latter is used.

Another object of the invention is the provision of a bolster stabilizer designed to produce a constant frictional condition or relation with the adjacent portions of the truck frame, with a light or loaded car; and in which the friction producing condition is mechanically obtained without prior friction spring compression in the bolsters before assembly into a side frame or without manually compressing the friction springs after the bolsters are assembled in the side frames; a construction wherein the friction elements exert no variable pressure during the vertical or up and down movements of the bolster.

A further object of my invention is simplicity, in design, in application and in maintenance and in initial cost, with the various parts having comparatively large and substantially flat frictional contacting surfaces ensuring continuous operation as a result of the use of a single vertically operating coil spring in each bolster end pocket

2

which ensures constant friction shoe pressure under a light or loaded car at all bolster positions; a construction wherein the contained spring of the stabilizer may be easily regulated by the introduction of suitable shims either at the top or at the bottom of the enclosed friction producing spring to compensate for wear of the shoes or adjacent elements, without the necessity of removal of the bolster and its contained stabilizing elements.

The objects and advantages of the invention will be readily comprehended from the following detailed description of the accompanying drawings wherein:

Figure 1 is a plan view of one end of a truck bolster with the stabilizing means receiving pocket shown in dotted lines and the load springs shown in dotted and full lines while the stabilizing means are omitted.

Figure 2 is a side elevation of the bolster end shown in Figure 1.

Figure 3 is an outside elevation of the intermediate or window opening portion of a truck side frame with the inserted end of the bolster showing the inserted stabilizing means in dotted lines, and the bolster supporting springs in elevation.

Figure 4 is a cross sectional view at the end of the bolster and of the contained stabilizing means in operative position, taken on line 4—4 of Figure 5, with a portion of the side frame and supporting springs shown in side elevation.

Figure 5 is a sectional view taken on the line 5—5 of Figure 4, showing the operative position of the elements under a light or loaded car.

Figures 6 and 7 are sectional views taken on the same lines as Figures 4 and 5, but showing the bolster in its extreme raised or jacked up position for application or removal of the bolster supporting springs, with the stabilizing elements in contracted or non-friction applying position.

Figure 8 is a top plan view of my improved wedge element.

Figure 9 is a side elevation of the wedge element as viewed from a side of Figure 8.

Figure 10 is a top plan view of one of the friction elements or blocks.

Figure 11 is a side elevation of the same.

Figures 12 and 13 are views similar to Figures 10 and 11 showing the companion friction block; Figures 8, 10 and 12 in reality constituting what may be termed an exploded view of the stabilizing means with the respective elements positioned to be brought together in assembled operative position.

Figure 14 is a bottom plan view of the friction elements or blocks (both friction blocks being similar).

Figure 15 shows the spring holding cup in side elevation.

Figure 16 is a side elevation of the cup as viewed at right angles to Figure 15.

Figure 17 is a bottom plan view of the cup.

Figure 18 shows the friction spring in position to enter the wedge block, Figure 9, and the spring cup as shown in Figure 15.

Figure 19 is an elevation of a portion of one end of the bolster with the stabilizing means shown in dotted lines and in release or non-friction applying position.

In the particular exemplification, my invention is shown applied to a standard truss type of railroad car truck frame 25, the intermediate or window-opening portion of which is shown at 25^a with the window-columns 26, 26 which are preferably provided with wear plates as at 27, 27.

The window-opening 25^a is intended to receive one end of the truck bolster 28, provided with the usual guide lugs or ribs 29 as shown in Figure 1, adapted to overlap the columns 26 of the side frame. The structure thus far described is the standard A. A. R. type of truck frame and bolster arrangement.

In order to receive my improved stabilizing means, the bolster 28 adjacent its ends is of box-like or hollow construction and provided at each end with a top wall 28^b; a bottom wall 28^c and a pair of longitudinally spaced webs or partitions 30, 30 as shown in dotted lines in Figure 1 and in full lines in Figures 5 and 7 to provide a plane four-walled chamber or pocket therebetween which is open at opposite sides of the bolster and with a central bottom opening at 28^a; the walls or partitions 30, 30 at the side openings being preferably off-set or recessed at 31, 31 to receive the outer ends or heads of the friction elements 32, 32; the laterally extended ends or heads being shown at 33; see Figures 10 and 12, which provide wide bearing or friction surfaces for engaging the wear plates 27, 27. As both friction blocks 32, 32 are identical a description of one will suffice. These blocks or shoes which are preferably hollow rectangular castings with flat tops and bottoms and outer plane ends—at their inner ends are each formed with an upwardly and inwardly inclining surface 34 and may be somewhat inset intermediate opposite sides at the top of the block, as shown at 35; while the bottom of the block intermediate its sides may be provided with an extension or lug 36, preferably of round contour, for a purpose hereinafter to be described; the bottom of the block being shown provided with a substantially semi-circular socket 37 in the side of the block for a purpose hereinafter described.

These friction blocks 32, 32 are inserted from each end of the pocket in the bolster (two blocks for each pocket) and are intended to cooperate with an intermediate wedge element or block 38 of rectangular configuration as shown in Figure 8 and consisting preferably of a hollow casting disposed transversely of the bolster with its sloping or inclining ends 39, 39 matching and intended to cooperate with the sloping surfaces 34, 34 of the adjacent friction blocks 32, 32. The wedge block or element 38 at its bottom may have depending lips 40, 40 which rest on the floor or bottom of the bolster 28 when in lowered or non-wedging position. As is apparent, when the

wedge block 38 moves upwardly (the block 38 being of less height than the vertical dimensions of the pocket in the bolster), the friction blocks 32, 32 will be forced outwardly through the open ends of the pocket, namely outwardly at opposite sides of the bolster and into frictional engagement with the wear plates 27, 27 on the columns 26, 26 of the truck frame.

The wedge element or block 38 is made hollow with a substantially flat top to receive the upper end of a friction spring 41 positioned as shown in Figure 18, while the lower end of the spring 41 seats in a spring holding cup 42 which is adapted to fit into the opening 28^a and flush with the bottom of the bolster all as shown in Figures 4 and 5.

The cup 42 is shown provided with a flat bottom and the side walls at opposite sides provided with upstanding guide arms 43, 43 which are slightly off-set outwardly, as more clearly shown in Figure 17, and are intended to fit into the laterally off-set portions 28^b in the opening 28 in the bolster-bottom, shown in dotted lines in Figure 1, to prevent rotation of the spring cup. The cup 42 also is provided with upstanding arms 44 at diametrically opposite points intermediate the pair of arms 43; and these arms 44 may be each provided with a vertically arranged slot 45 intended to receive the extension or lug 36 of the adjacent friction block, as shown in Figures 3, 4 and 6; the lugs 36 of the two oppositely arranged friction blocks are intended to hold the cup from dropping out of the bolster opening.

The outer end wall or partition 39 in the bolster at the bottom of the bolster is shown provided with a pair of openings at 46 which are adapted to align with the sockets 37 in the lower parts of the friction blocks 32, 32 during assembly of the stabilizing means, for the purpose of receiving a small wood dowel or any soft shearable material, whereby the respective friction elements will be temporarily held in retracted position within the bolster-pockets and thus allow the ends of the bolster to be inserted in proper position between the columns 26, 26 of the truck frame.

My improved stabilizing means is assembled by first inserting the wedge element or block 38 through one end of the bolster-pocket and placing it across the bottom opening 28^a; then inserting cup 42 with friction spring 41 through the bottom opening 28^a with the upper end of the spring entering into the hollow wedge block 38; the cup being pressed up sufficiently to bring the upper ends of the slots 45, 45 in arms 44, 44, a short distance above the bottom of the pocket and the cup temporarily held in this position. The friction blocks 32, 32 are then inserted through their respective ends of the pocket, with their sloping surfaces 34, 34 in contact with the inclining surfaces 39, 39 of the wedge block 38, at which time the extensions or lugs 36, 36 of the friction blocks 32, 32 will enter the respective slots 45 of the spring cup 42; the friction blocks being then temporarily held in position entirely within the bolster-pocket by inserting a soft shearable element or wood dowel in the registering holes in the outer pocket wall and bottoms of the friction blocks. The bolster, with the assembled stabilizing means, may then be inserted in place in the truck frame, as the lugs on the retracted friction blocks will hold the spring cup from dropping out of the bolster-bottom opening. The main portion of the wedge

block 38 is held above the floor of the bolster-pocket by the depending lips 40 at the ends, thus providing passage for the extensions or lugs 36 of the friction blocks.

The bolsters positioned in the side frames are then jacked up for the placing of the load springs 47 of standard or other grouping. Bolsters with contained stabilizing parts mounted in truck frames are then brought from an inoperative to an operative position by placing a car body on a pair of truck bolsters. This added weight moves the bolsters downward compressing the load or bolster supporting springs to their light car operating height. Spring cup 42 with contained spring 41 contacting a part of these load springs will be urged through bolster bottom floor opening 28^a to its operating position flush with the bolster bottom floor. Spring 41 will be positioned at its proper operating height and the upper end of this spring contacting the wedge member will urge this member to its operating position, the wedge member contacting the angular inner faces of the friction shoes, moves these members upwardly and outwardly into bolster and side frame contact, shearable friction shoe retaining means if left in holes 46, 46 would be sheared off by the movement of the friction shoes.

Should it be desired at any time to increase friction spring pressure to compensate for shoe face wear or for other causes, a shim inserted at either the upper or lower end of the friction spring can simply and easily be applied.

Inasmuch as load springs 47 contact both the spring cup 42 and the bolster bottom floor 28^a any movement of the cup 42 beyond a flush bolster position would be mechanically impossible.

The exemplification disclosed in the drawings is believed to be a simple embodiment of the invention but structural modifications may be possible without, however, departing from the spirit of my invention as defined in the appended claims.

What I claim is:

1. In a railway car truck bolster stabilizer, the combination of a truck side frame with a bolster receiving opening having side columns, bolster supporting springs arranged in the bottom of said opening, a bolster resting on said supporting springs provided with transversely disposed four plane walled pockets at the ends and open at the sides of the bolster with a central opening in each pocket through the bottom of the bolster; a pair of friction blocks having upwardly sloping inner ends, slideable in the ends of each pocket and adapted to frictionally engage the truck frame columns; a hollow wedge block arranged in each pocket between the inner ends of the friction blocks, the adjacent portions of the friction blocks and said wedge block having matching sloping surfaces in contact with each other whereby the friction blocks are forced through the open ends of the pocket when the wedge block moves upwardly in the pocket; a vertically extending coil spring and a spring holding cup insertible through said bolster-bottom opening with the upper end of the spring bearing against the inner surface of the top of the wedge block and exerting constant upward pressure on the wedge block, the bottom of said cup being adapted to extend flush with the bolster-bottom and to be so maintained by the bolster supporting springs without affecting the pressure of said cup spring.

2. In a railway car truck bolster stabilizer, a

truck side frame with a bolster end receiving opening, a bolster provided with a four walled pocket in each end and with self contained stabilizing means in each pocket consisting of laterally movable friction blocks, a vertically movable hollow wedge block between the inner ends of the friction blocks and adjacent ends of the wedge block having matching sloping faces, a spring holding cup beneath the wedge block, a vertically disposed coil spring seated in said cup with its upper end arranged in the wedge block and exerting upward pressure on said wedge block, the inner ends of the friction blocks and said spring holding cup having interengaging surfaces whereby the cup is held in the bolster when the friction blocks are out of contact with the side frame.

3. In a railway car truck bolster stabilizer, the combination of a truck side frame with a bolster receiving opening having bolster supporting springs in the bottom, a bolster whose end extends into said frame opening and rests on said supporting spring provided with an opening in its bottom, openings in the sides and self contained stabilizing means in each end involving friction blocks laterally movable through said side openings, a hollow vertically movable wedge block open at the bottom, a coil spring holding rigid member with upstanding portions arranged in the bolster bottom opening beneath the open bottom of the wedge block and supported in place by said supporting springs, a vertically disposed coil spring seated on said rigid member with the upper end of the coil spring extending into the hollow wedge block and exerting upward pressure on the wedge block to cause the latter to move upward and thereby force the friction blocks into frictional engagement with the side frame, and means carried by said friction blocks and arranged in operative engagement with upstanding portions of said rigid member whereby the rigid member is held suspended in the bolster bottom opening when the bolster is free of the supporting springs and thus permit the wedge block spring to expand.

4. In a railway car truck bolster stabilizer, the combination of truck side frames with bolster end receiving openings and bolster supporting springs; with a bolster, adapted to extend into said frame openings, provided with transversely disposed pockets at the ends and open at the sides and bottom of the bolster, each pocket containing a pair of friction blocks transversely slideable in a pocket of the bolster and adapted to effect frictional engagement with the side frame, a vertically movable hollow wedge block between the friction blocks and in pressure exerting engagement with the inner ends thereof, a coil spring arranged in each pocket and disposed upwardly into the wedge block to exert uniform upward pressure on the wedge block, and means, supported by said bolster supporting springs, whereby the coil spring is maintained within the wedge block to exert upward pressure.

5. In a railway car truck bolster stabilizer, truck side frames with bolster receiving openings, a spring supported bolster provided adjacent its ends with transversely arranged pockets open at the sides of the bolster and with openings through the bottom of the bolster communicating with said pockets; hollow wedge blocks and cooperating friction blocks insertible through the open ends of said pockets the friction blocks being disposed at opposite sides of each wedge block and adapted to extend through the

openings in the bolster sides, the friction blocks and wedge blocks having complementary surfaces whereby the friction blocks are simultaneously caused to move laterally outward into frictional engagement with the adjacent portions of the bolster and of the truck side frame through the upward pressure of the wedge blocks; wedge block controlling springs adapted to fit into said wedge blocks to exert constant upward pressure on said blocks; and spring holding means adapted to effect interengaging relation with the friction blocks to prevent displacement of said means through the openings in the bolster bottom; said springs and spring holding means being insertible through said bottom openings with said holding means adapted to extend substantially flush with the bolster bottom and be supported in place by the bolster load carrying springs.

6. In a railway car truck bolster stabilizer, the combination of a truck side frame with a bolster end receiving opening and load carrying springs, a bolster provided at the ends with transversely disposed pockets open at the sides of the bolster and having openings through the bottom of the bolster; a pair of friction members arranged in each pocket, hollow wedge blocks arranged intermediate the friction blocks; vertically disposed coil springs arranged in said hollow wedge blocks to exert constant upward pressure on the wedge blocks; spring holding means arranged in said bolster-bottom openings, said spring holding means and friction blocks having lug-and-slot interengaging connections for holding said means with the superposed springs in position during assembly, said spring holding means being held flush with the bolster bottom by the load carrying springs, when the bolster is in operative position.

7. In a railroad car truck bolster stabilizer, the combination of truck side frames with bolster end receiving openings and load supporting springs in said openings, a bolster provided adjacent the ends with transversely disposed straight walled pockets open at the bolster sides and having openings through the bolster bottom at the bolster median line; stabilizing means arranged in said pockets consisting of friction blocks having plane top, bottom, sides and outer end walls and sloping inner ends, wedge members with sloping ends matching the sloping inner ends of the friction blocks for forcing the ends of the friction blocks through the open ends of the pockets into engagement with the upper wall of the bolster and with the adjacent side frame, vertically disposed coil springs arranged in the wedge members for forcing the latter upwardly and into wedging relation with the friction blocks, spring supporting members for said vertically disposed springs insertible in the bolster bottom openings and maintained flush with the bolster bottom by said bolster supporting springs, and means associated with said friction blocks arranged to have controlling relation with said spring supporting members whereby the latter are held suspended in the bolster bottom openings and the wedge members relieved of spring pressure when the bolster is out of contact with said load supporting springs.

8. In a railway car truck bolster stabilizer, the combination of a truck side frame with a column at each side of a bolster-opening, a bolster having an end substantially rectangular in cross section and arranged in said opening, bolster

supporting springs arranged in the bottom of said opening, the bolster ends being each formed with a transversely extending substantially rectangular pocket open at the sides of the bolster and having a bottom opening at the vertical median line of the pocket, a pair of friction shoes arranged in each pocket on opposite sides of said bottom opening and having upwardly and inwardly sloping inner ends with flat top, bottom, sides and outer end walls and adapted to move horizontally outward through said openings in the bolster sides into bolster and column contact; a hollow wedge block seated over the bottom opening in the bolster and provided with upwardly and inwardly inclined ends matching the sloping ends of the friction shoes on opposite sides thereof; a vertically disposed coil spring arranged within said wedge block to constantly exert upward pressure on said wedge block so as to move said wedge block into frictional engagement with said friction shoes; and a removable cup-like member for the lower end of said coil spring formed to seat in said bottom central opening in the bolster and extend flush with the bolster bottom; said cup-like member being adapted to be held to its seat by the bolster supporting springs.

9. In a railway car truck bolster stabilizer, truck side frames with window openings, bolster supporting spring means seated in the bottoms of said openings, and a bolster whose ends extend into said window openings and rest on said spring means, the bolster ends being formed with rectangular straight walled pockets extending transversely and having openings at the bolster sides and with a central opening in the bottom, bolster stabilizing means arranged entirely within said pockets, comprising a pair of rectangular friction shoes in each pocket at opposite sides of said bottom opening and in slidable contact with the top wall of the pockets, provided with plane outer ends slidably engaging non-movable portions of the truck defining said window openings and having upwardly and inwardly sloping inner ends, a hollow wedge block with an open bottom between the inner ends of each pair of shoes and having sloping sides matching the inner ends of the shoes and in constant contact therewith, a vertically disposed coil spring arranged in each wedge block in pressing relation with the upper wall of the wedge block thereby forcing the shoes into frictional engagement with the side walls of the window openings; and a supporting member for the lower end of each coil spring, seatable in the bottom opening in the bolster so as to extend flush with the bottom and to be supported in place by the bolster supporting springs, whereby the friction shoes are under constant outwardly forcing pressure, and means whereby the friction shoes may be temporarily held in retracted position during assembly of the bolster in the window openings of the truck frame.

10. In a railway car truck provided with load supporting springs, and a bolster with plane four walled transverse pockets with openings at the sides and in the bottom floor, resting on said springs, stabilizing means housed in the bolster pockets, comprising, friction shoes with upwardly and inwardly sloping inner faces mounted in opposite sides of said pockets, hollow open bottom wedge members arranged entirely within said bolster pockets, positioned between and contacting the angular inner faces of the shoes, for simultaneously urging the upper surfaces of the

shoes into bolster top contact and their outer ends into frictional contact with non-movable portions of the truck adjacent the outer ends of the shoes, spring supporting members positioned beneath said wedge members in the bolster bottom opening and having upstanding portions disposed above the bolster bottom, vertically disposed coil springs seated on said spring supporting members with their upper ends extending into and maintaining constant upward pressure on said wedge members, the bottom of said spring supporting members being adapted to extend flush with the bolster spring seat and to be so maintained by the bolster supporting springs, and means movable on the bolster bottom, constituting a part of the stabilizing means, arranged to automatically effect holding relation with said upstanding portions of the spring supporting members to hold the latter in suspended position when said supporting members are free of the load supporting springs.

11. In a car truck, the combination of truck side frames with bolster end receiving openings, wear receiving means; a truck bolster whose ends extend into said frame openings; spring means arranged in said openings for yieldingly supporting the bolster; bolster stabilizing means consisting of a plurality of cooperating movable elements arranged within the bolster ends and involving a pair of friction blocks having flat top and outer side surfaces and inner inwardly sloping surfaces; an upwardly movable hollow wedge member having upwardly and inwardly sloping outer surfaces complementary to and in constant engagement with the inner surfaces of said blocks and disposed vertically between said blocks; an independent spring arranged vertically in said wedge member in contact with the top wall thereof for constantly urging said wedge member upwardly and maintaining the complementary faces in yielding engagement and thereby causing the friction blocks to exert upward pressure on the bolster and said blocks to move laterally into friction engagement with the wear receiving means of the truck; and a rigid member at the bottom of said independent spring, supported in operative position by the first mentioned spring means when the bolster is supported by said means, for supporting said independent spring and formed to have interengaging relation with certain of the movable elements of the stabilizing means and thereby hold the rigid member against dissociation with said independent spring when the bolster is out of contact with said first mentioned spring means.

12. In a railway car truck bolster stabilizer, a truck side frame provided with a bolster end receiving opening and bolster supporting springs, a bolster provided with transversely disposed pockets adjacent the ends open at opposite sides of the bolster and having openings through the bottom; a pair of friction blocks slidably arranged in each pocket and having inner sloping ends and adapted to contact the top wall of the pocket and the adjacent portions of the truck frame, the friction blocks at their bottoms hav-

ing extensions disposed inwardly toward each other at opposite sides of the bolster bottom opening; a hollow open bottom wedge block in each pocket intermediate the pair of friction blocks and having sloping surfaces matching and in contact with the sloping surfaces of the friction blocks; means whereby the wedge block is held spaced from the bolster bottom to provide passage for the friction block extensions; pressure springs arranged in each wedge block for forcing the latter upwardly and thereby control the wedging relation between the wedge blocks and the friction blocks; a rigid member for supporting the pressure spring and arranged in the bolster bottom opening and formed to effect interengaging holding relation with said friction block extensions whereby said rigid member is held suspended in the bolster bottom opening and the pressure springs permitted to expand out of wedge block pressure condition when the bolster is out of contact with the supporting springs.

13. In a railway car truck bolster stabilizer, a side frame provided with a bolster opening, a bolster having an end portion extending into said bolster opening, said bolster having a transversely disposed pocket open at opposite sides of the bolster and having an opening through the bottom of the bolster, a pair of friction shoes with sloping inner ends slidably arranged in the pocket and adapted to contact adjacent portions of the side frame, the shoes at their inner ends having horizontally extending lugs disposed toward the bottom opening, a wedge member in said pocket intermediate the friction shoes having end sloping surfaces in contact with the sloping inner ends of the friction shoes, a vertically disposed spring arranged under said wedge member moving it upwardly to urge the friction shoes into engagement with the side frame, a rigid member engaging the lower end of said spring arranged in the opening at the bottom of the bolster, said rigid member being formed to effect interengaging relation with the friction shoe lug whereby the rigid member is permitted to drop in the bolster bottom opening and allow said wedge spring to expand out of wedge pressure condition during assembly, and load supporting springs carried by the side frame engaging said bolster end portion and said rigid member maintaining the same in position compressing said spring.

KARL M. HAMILTON.
